United States Patent Office

Des. 185,643
Patented July 7, 1959

185,643

WATER CLOSET

Hyman S. Magid, Morrisville, Pa., and William H. McKinney, Lisbon, Conn., assignors to American Radiator & Standard Sanitary Corporation, New York, N.Y., a corporation of Delaware

Application April 23, 1958, Serial No. 50,584

Term of patent 14 years

(Cl. D4—5)

Fig. 1 is a top plan view of a water closet, showing our new design;

Fig. 2 is a view in side elevation of the water closet;

Fig. 3 is a view in front elevation thereof; and

Fig. 4 is a view in rear elevation thereof.

We claim:

The ornamental design for a water closet, substantially as shown.
